UNITED STATES PATENT OFFICE.

LUDWIG C. BERG, OF TACOMA, WASHINGTON.

SYRINGE.

Application filed February 16, 1928. Serial No. 254,666.

My present invention relates to an improved syringe which while adapted especially for use by invalids is also applicable for various uses of a rectal syringe or douche, either by bed-ridden invalids or by those able to use the toilet facilities of a bath room or similar place. By the utilization of the device of my invention the person requiring the douche may with facility and convenience manipulate the parts for the purpose, or they may be manipulated or handled with equal facility by a nurse or attendant, and the parts are combined and arranged in such manner that the nozzle may be applied and the douche given or administered with quickness and dispatch and with comfort to the user.

The invention consists in certain novel combinations and arrangements of parts as will hereinafter be more fully set forth and claimed. In the accompanying drawings I have illustrated one complete example of the physical embodiment of my invention where-in the parts are combined and arranged according to the best mode I have thus far devised for the practical application of the principles of my invention.

Figure 1 is a view showing the device of my invention in position for use. Figure 2 is an enlarged detail view partly in section showing the attaching feature and the valve for the syringe. Figure 3 is an enlarged detail of the nozzle of Figure 1 and Figure 3^a is a cross section at line 3—3^a of Figure 3. Figure 4 is a perspective view showing the handle, and Figure 5 is a longitudinal sectional view of the handle. Figure 6 is a view showing various nozzles for use with the syringe. Figure 7 shows a modified form of handle.

In Figure 1 I have shown the general assembly and arrangement of parts ready for use in connection with a bowl B, the seat S and the water tank T. The invention contemplates the use of a metallic tubing 1 fashioned with curves and bends to a formation adapting it to be placed in position with relation to the bowl and seat and to conform to the body of the user, there being a nozzle 2 shown in place in Figure 1 ready for use.

The tube 1 is adapted to be supported on the top of the seat S and is fashioned with a bearing head or cushion 3 at its under side for contact with the top of the seat, and a clamp hook 4 co-acts with the bearing head for supporting the apparatus.

The hook is preferably formed with an arm 4' that rests directly across the top of the seat and this arm is rigid with or integral with a bushing 5 that is slideable and adjustable on the tube 1. A friction plate 6 is shown within the bushing for contact with the tube and a set screw or bolt 7 threaded in the bushing impinges against this plate to force into frictional contact with the tube and hold the bushing in rigid relation with the tube in its adjusted position. The clamping device may thus with facility be adjusted to suit different conditions and be spaced at various distances from the nozzle 2.

A valve casing 8 is interposed in the tubing and a valve 9 in the casing controls the flow of water or other douche through the tube, which tube is provided with the usual enlargement or head 10 for the hose 11. The hose is attached to the tank T in usual manner or may be attached to other desired container used to provide the douche.

For convenience and comfort in holding or maintaining the nozzle in proper position a handle is provided on the tube.

The handle is preferably fashioned with a flat tubular casing 12 having an open top and side flanges and secured, as by welding or brazing, to the tube 1. At its ends the casing is provided with turned up lugs 13 to form stops, and the two top flanges are provided with two series of complementary holes 14 that are utilized for locking the adjustable, bowed, handle 15 in place. The bowed handle is preferably fashioned from resilient metal and provided at one end with a transversely extending head 16 and at its other end with a pair of upwardly extending lugs 17, the latter adapted to be inserted in a pair of holes or openings of the complementary series 14. A friction spring 18 is fashioned on the handle for frictional engagement with the top of the inner part of the casing and this spring performs the function of holding the lugs upwardly inserted in the pair of holes 14, thus preventing displacement of the handle after it has been set in adjusted position. The transversely extending head 16 retains the rear end of the spring or bowed handle in position and prevents its displacement.

The syringe may be used for various purposes, and it will be understood that the nozzle 2 may be dispensed with and one of the nozzles 19, 20 or 21 of Figure 6 substituted therefor in carrying out these uses.

In Figure 7 a modified form of handle 22 is shown, which is preferably of rubber, and frictionally engages the tube to hold it in adjusted position.

5 Having thus fully described my invention what I claim as new and desire to secure by Letters Patent is:—

1. The combination with a rigid tube having a nozzle and a bearing head thereon, of an 10 adjustable bushing on the tube and retaining means therefor, a resilient clamp hook on the bushing for co-action with the bearing head, a valve in the tube and a hose connected to the tube for the purpose described.
- 15 2. The combination with a rigid tube having a nozzle, means for clamping the tube in position, and means for supplying a douche to the tube, of a handle-casing on the tube, an adjustable handle, and co-acting means on the 20 handle and casing for holding the former in adjusted position.

3. The combination with a syringe tube, of a handle casing having an open top and lateral flanges with two series of complementary holes therein, a bowed resilient handle having a transverse retaining head for co-action with the flanges, and upwardly turned lugs on the handle for engagement with a pair of holes.

4. The combination with a syringe tube 25 curved and bent to conform to a toilet seat and a bearing head on the underside of said tube, of a sliding bushing on the tube, a friction plate between the bushing and tube and a set screw in the bushing for impinging the plate 30 on the tube, a resilient hook on the bushing for co-action with the bearing head, a valve in the tube, and a hose connected to said tube.

In testimony whereof I affix my signature.

LUDWIG C. BERG.
